UNITED STATES PATENT OFFICE.

THEODORE G. LEWIS AND FREDERICK M. BAILEY, OF BUFFALO, NEW YORK,
ASSIGNORS TO THE BUFFALO DENTAL MANUFACTURING COMPANY, OF
SAME PLACE.

DESIGN FOR A BRAZING-STAND.

SPECIFICATION forming part of Design No. 27,747, dated October 19, 1897.

Application filed February 19, 1897. Serial No. 624,249. Term of patent 7 years.

To all whom it may concern:

Be it known that we, THEODORE G. LEWIS and FREDERICK M. BAILEY, citizens of the United States, residing at Buffalo, in the county of Erie and State of New York, have invented and produced a new and original Design for Brazing-Stands, of which the following is a specification, reference being had to the accompanying drawings, forming a part thereof.

This design relates to the shape or configuration of the stands or tables which are employed for supporting the blow-pipes, air-reservoir, and other accessories of brazing appliances, and which are commonly known as "brazing-stands."

In the accompanying drawings, Figure 1 is a perspective view of a brazing-stand embodying our design. Fig. 2 is a detached top plan view of the bed or top frame of the stand.

Like letters of reference refer to like parts in both figures.

The end frames of the stand are each composed of upright side bars A, an upper cross-bar A', connecting the upper ends of the side bars, a lower cross-bar A'', connecting the lower portions of the side bars, and curved legs A³, extending laterally or outwardly beyond the side bars and forming with the latter a compound or ogee curve, as shown in Fig. 1. The legs terminate in ornamental feet a. The side bars are curved outwardly at their upper ends, as shown at a', and the side bars, the upper and lower cross-bars A' A'', and the legs A³ are relieved by raised marginal ribs or flanges, as shown in Fig. 1. The lower cross-bar A'' has in its middle an opening a², and the bar has a curved swell or bulge a³ on the upper and lower sides of this opening.

The side frames which connect the end

frames are approximately rectangular and have straight upper and lower edges B B', concave ends, and a comparatively large central opening B² of circular form. In each of the four triangular spaces located in the corners 45 of the side frame is an irregularly-shaped opening b, the outer side of which is concentric with the adjacent concave end of the frame, forming at each end of the frame a segmental or inwardly-curved bar B³. The side 50 frame, its circular opening B², and the corner openings b are bounded by raised marginal ribs or flanges, as shown. Between each pair of triangular openings on the same side of the central opening are webs b³, in each of which 55 is an opening b¹, and in each of the spaces between the large central opening and the irregular openings b is a circular opening b⁵.

The top or bed-plate is oblong in form and composed of side bars C and end bars C'. 60 The plate is rounded at the corners and at its lower edge is a rectangular inwardly-extending flange c. On each side bar C is a laterally-projecting wing c', which extends nearly to the ends of the top plate, and in each of these 65 wings is a longitudinal slot c². Projecting from the corners of the top plate are ears c³, and in each corner of the inwardly-extending flange is located a pair of diagonally-arranged openings c⁴. 70

What we claim is—

The design for a brazing-stand, substantially as herein shown and described.

Witness our hands this 16th day of February, 1897.

THEODORE G. LEWIS.
FRED. M. BAILEY.
